UNITED STATES PATENT OFFICE.

JOHN W. MEAKER, OF DETROIT, MICHIGAN.

SPARK-PLUG.

1,156,796.

Specification of Letters Patent. Patented Oct. 12, 1915.

Application filed October 5, 1912. Serial No. 724,007.

To all whom it may concern:

Be it known that I, JOHN W. MEAKER, a citizen of the United States of America, residing at Detroit, in the county of Wayne and State of Michigan, have invented certain new and useful Improvements in Spark-Plugs, of which the following is a specification, reference being had therein to the accompanying drawings.

10 In the use of spark plugs, as the ignition terminals of explosive engines are customarily called, it is necessary for their successful operation that the difference in the coefficients of expansion in the different parts be provided for and that leakage be prevented under the high pressures to which they are subjected. It is also desirable that the operation of the plug be observable.

This invention relates to spark plugs for 20 explosive engines and to an arrangement thereof whereby tight joints are obtained which hold under the severe strains and stresses of expansion and pressure to which the plugs are subjected.

25 The invention also includes means whereby not only the operation of the plug can be observable but the spark thereof be made more efficient and whereby the sparking terminals when once adjusted maintain their relative positions so as to preserve the proper gap and do not sag or become otherwise displaced when heated.

The invention consists in the matters hereinafter set forth and pointed out in the appended claim.

In the drawings, Figure 1 is a view partially in elevation and partially in section, of one form of spark plug that embodies features of the invention; Fig. 2 is a cross 40 sectional view taken on or about line II—II of Fig. 1; Fig. 3 is a bottom plan view of Fig. 1; Fig. 4 is a view enlarged and in detail showing the method of securing a terminal rod with provision for expansion; Fig. 45 5 is a view in detail showing a modification of a body structure; Fig. 6 is a bottom plan view showing one form of ignition gap; Fig. 7 is a view in detail in longitudinal section showing an arrangement for ready 50 cleaning of the terminals; Fig. 8 is a view in detail showing a modification of a signal gap terminal; Figs. 9 and 10 show modifications of the invention; and Figs. 11, 12, 13, 14 and 15 show different forms of the ignition gap terminals and which provide for 55 an adjustment thereof.

Referring to the drawings a body 1 of insulating material with tapered lower portion 2 has an intermediate flange 3 that is seated in a centrally apertured nipple 4, the latter being exteriorly screwthreaded for insertion in the spark plug opening of a cylinder. An annular collar 5 in screwthreaded engagement with the nipple 4 holds the body in position and closes the joint by compression of a suitable washer 6 over the upper face of the flange 3.

The insulating body 1 (as indicated in Fig. 5) may be seated on the upper end of a cylindrical nipple 7 and held in position by 70 an outer sleeve 8 that is forced downwardly thereover against a packing ring 9, the sleeve being permanently secured in position as by holding pins 10 through the superposed walls 75 of the sleeve and nipple.

A central terminal rod 11 extends through an axial aperture of the body 1 with a lower head or flange portion 12 that bears against a suitable washer 13 and is itself in operative relation to ignition terminal members 80 14 secured on the lower end of the nipple 4 or the like. A counterbored recess in the upper end portion of the body 1 affords a seat for a packing ring 15 that encircles the stem. A spring washer 16 or the like in 85 compression between the packing ring 15 and the signal terminal head 17 screwthreaded on to the member 11 holds the latter in position regardless of expansion of it and the surrounding body and maintains a 90 tight joint under all working conditions. Preferably the head 17 engages the washer 16 to center it in the recess.

The plug is preferably provided with signal gap terminals on its upper end which 95 furnish visible means for determining the condition of the plug. As indicated in Figs. 1, 2 and 4 a terminal cap 18 to which suitable electrical connection may be made is rotatably secured on the upper end portion 100 of the body 1 and may have an eccentric flange 19 encircling the head 17 of the member 11, rotation of the cap furnishing means for varying the gap between the head 17 and flange. Or as shown in Figs. 8 and 9 the 105 flange of the cap may have two or more projections 20 of different length with which the head of the stem may be brought into register to vary the spark as preferred. Between the projections the maximum gap or 110 spark length is obtained, for use in clearing the firing gap. As before stated the head

may be of any preferred form, and in these figures 8 and 9 is made by simply bending the stem laterally beyond a supporting flange 21.

- 5 The electrodes which form the ignition gap at the other end of the spark plug are supported on the projecting end of the nipple in operative relation to the end of the rod 11. The body electrodes may be between
- 10 wire loops 14 as shown in Figs. 1 and 3 which may be bent back and forth as desired to furnish proper adjustment, or there may be a single loop 22 as shown in Fig. 11. Preferably the loops are inclined to allow
- 15 for drainage therefrom of any oil or the like. Other forms of gap terminals are shown in Figs. 13, 13, 14 and 15 in which the loop has its head portion 23 secured in suitable openings through the nipple with arms
- 20 25 encircling the stem and lying in a lateral slot in the nipple. The spreading of these arms regulates the double gap.
- If the spark gap terminals have the form shown in Fig. 11 in fixed relation, it is somewhat difficult to clean them and provision is made as indicated in Fig. 7, by inserting a bushing 26 in the lower end of the nipple, the bushing being readily removable for removing carbon or other foreign material.
- 30 As a result of this construction a spark plug is obtained in which the packing is so disposed that the joints are tight under all conditions or service, and a visible gap is provided that readily shows the condition
- 35 of the plug and furthermore enhances the calorific properties of the sparking gap owing to the temporary retardation of the latter and likewise has adjustable terminals for both gaps. Some forms shown herein
- 40 make the construction very inexpensive as

well as effective. The adjustable feature of the signal gap permits the user to entirely cut out the latter or to regulate it to any preferred length.

Obviously, changes in the details of construction may be made without departing from the spirit of my invention and I do not care to limit myself to any particular form or arrangement of parts.

What I claim is:—

In a spark plug, a nipple, a body of insulating material secured therein by means effectively sealing the joints between the body and nipple, a terminal member extending through the body, the nipple with the contained body, terminal and securing means forming in effect an integral structure, and a bushing detachably secured to the lower end of the nipple and provided with electrodes adapted to coöperate with the terminal and forming a part of the said integral structure when the latter is applied to the bushing, the bushing providing means for maintaining the integral structure in a motor whereby the integral structure may be bodily removed and replaced without disturbance of the parts, and the nipple so housing the bushing when the plug is mounted in a motor that the bushing and the joint between the bushing and nipple are concealed, the bushing and nipple coating to maintain the proper spark gap whenever reassembled.

In testimony whereof I affix my signature in presence of two witnesses.

JOHN W. MEAKER.
